UNITED STATES PATENT OFFICE.

WILLIAM F. HELMOND, OF HARTFORD, CONNECTICUT, ASSIGNOR TO UNDERWOOD ELLIOTT FISHER COMPANY, OF NEW YORK, N. Y., A CORPORATION OF DELAWARE.

TYPEWRITING MACHINE.

Application filed July 3, 1926. Serial No. 120,351.

This invention relates to paper-fingers on typewriters for holding the work upon a rotary platen above the printing line.

Heretofore it has been the practice to swing a paper-finger out of the way to clear the leading edge of the work-sheet. However, according to this invention there is practically unobstructed insertion of the work-sheet while the paper-finger is in its effective position.

Another feature of this invention relates to the manner of constructing and assembling the paper-finger, which is cheapened while its usefulness is increased. The finger is pivotally mounted upon a bracket fast to the carriage-frame and is held in engagement with the platen, at a right angle thereto, by means of a spring of special construction. Said spring is effective to hold the paper-finger in both its effective and folded positions. Moreover, the spring permits a slight movement of the paper-finger upwardly to accommodate shifting of the platen and also to permit its deflection when the work-sheet is inserted.

The paper-finger is preferably made of a sheet-metal strip, wider at the supporting point and slightly tapered toward the free end thereof. Said free end is provided with a loop contacting with the platen at one point. The loop is partly closed at the rear thereof and terminates with a downwardly-extending deflecting piece which serves as a means to deviate or direct the leading edge of the sheet between the loop and the platen. At its supporting end the paper-finger is provided with a double bend through which the supporting pivot is passed.

When inserting a stiff paper or a card around the platen, the leading edge thereof engages the paper-finger in a manner to elevate its free end, thereby increasing the deflecting angle of the guiding plate, and further facilitating the introduction of the sheet under the finger. However, after the leading edge passes the finger the spring is strong enough to hold the paper against the platen.

Other features and advantages will hereinafter appear.

In the accompanying drawings,

Figure 1 is a perspective view showing the paper-finger in its effective position.

Figure 2 is a perspective view showing

the paper-finger in its folded or ineffective position.

Figure 3 is a cross-sectional view in elevation and shows the paper-finger as applied to an Underwood standard typewriting machine.

Figure 4 is a dismembered perspective view of the finger, the operating spring, the supporting bracket and the pivot screw.

The Underwood paper-carriage is provided with a front bar 10 which together with end frames 11 and a rear bar, not shown, serves as means for rigidly supporting a platen 12 rotatably mounted on a shaft 13. The platen is struck at the front thereof by type-bars 14.

A work-sheet 15 is inserted at the rear of the platen, over a rear table 16, and the leading edge of the sheet is engaged by feed-rolls 17 running on the platen. The platen is then rotated to position the work-sheet to the printing line.

The leading edge of the work-sheet engages, at the center thereof, a paper-finger indicated generally by the numeral 18. Owing to the peculiar construction of the paper-finger and also to the manner of mounting the same, the leading edge of the work-sheet is automatically guided under the finger while the same is in its effective position.

The finger is mounted on a pivot-screw 19 supported on a bracket 20 fast to the bar 10, the bracket being secured to the bar by means of a screw 21. In order that the finger may be slightly deflected when inserting the work-sheet to prevent wrinkling of its leading edge, there is pivoted a spring 22 which serves also as a means for holding the finger in both its effective and ineffective positions, as shown respectively in Figures 1 and 2. The spring is held in place by means of the screw 19 which passes through an elongated hole in a tongue 25 bent over from the spring and is laterally located on the bracket 20 by means of locating prongs or shoulders 23 and 24. The finger is loosely positioned between flanges or prongs 26 of the bracket 20, so as to permit movement thereof in all directions. To this end the finger is provided with a U-shaped or reflexly bent supporting end 27, the lower part thereof having a hole 28 for receiving the screw 19.

The upper part of the supporting end 27 is provided with an elongated hole 29 to permit

upward movement of the finger when the same is engaged by the work-sheet, as shown in dot-and-dash lines in Figure 3.

In order to prevent wrinkling the work-sheet when the leading edge thereof engages the finger 18, there is provided a deflector-plate 30 which conducts the work-sheet toward the platen. As shown in the drawings, the deflector plate forms an integral part of the finger and is a continuation of a loop 31 which bears upon the platen. The outer end of the deflector-plate is bent upwardly at 32 and is soldered to the finger at 33. To facilitate the swinging of the finger 18 to its effective or ineffective position, a half loop 34 serving as a finger-piece is provided which may be formed by bending the finger near its supporting end.

It will be understood that the finger may be left in its effective position during the insertion of a new sheet and need only be swung to its ineffective position in such cases as it may be desired to make erasures on the work-sheet or for any other reason.

Variations may be resorted to within the scope of the invention, and portions of the improvements may be used without others.

Having thus described my invention, I claim:

1. In a typewriting machine having a shiftable platen and a carriage therefor, a folding paper-finger arranged to contact with the platen above the printing line, and means for resiliently mounting said paper-finger upon the carriage in a manner to permit shifting of the platen, said means including a bracket fast to the carriage, a spring guided between prongs of said bracket, and a screw for holding the paper-finger in place when the same is in its folded position.

2. In a typewriting machine having a shiftable platen and a carriage therefor, a folding paper-finger arranged to contact with the platen above the printing line, and means for resiliently mounting said paper-finger upon the carriage in a manner to permit shifting of the platen, said means including a bracket secured to the carriage, a spring slidably mounted between the prongs of the bracket, means to guide said spring along said bracket-prongs against said finger, and a pivot secured upon said prongs to hold said finger in contact relation with said spring in extended and in folded positions.

3. In a typewriting machine having a shiftable platen and a non-shifting carriage therefor, a folding paper-finger arranged to contact with the platen above the printing line, and means for resiliently mounting said paper-finger upon the carriage in a manner to permit shifting of the platen, said means including a bracket having flanges and secured to the carriage, a spring

mounted between the flanges of the bracket and provided with locating shoulders projecting at the sides of said flanges, and a pivot-screw passing through said flanges and said finger beyond said spring.

4. In a typewriting machine having a shiftable platen and a non-shifting carriage therefor, a folding paper-finger normally arranged to contact with the platen above the printing line, and means for resiliently mounting said paper-finger upon the carriage in a manner to permit shifting of the platen, said means including a bracket having flanges and secured to the carriage, a spring mounted between the flanges of said bracket, said finger having a reflex bend mounted between said flanges against said spring, and a pivot-screw passing through apertures in said bracket and said bend, the aperture of said bend in said finger being enlarged to permit rocking movement of said finger against said spring.

5. In a typewriting machine having a shiftable platen and a non-shifting carriage therefor, a folding paper-finger arranged to contact with the platen above the printing line, and means for resiliently mounting said paper-finger upon the carriage in a manner to permit shifting of the platen, a bracket secured to said carriage and having a pair of flanges, a leaf-spring mounted at its intermediate portion between the flanges of said bracket and with the extremities thereof projecting to contact with said carriage, a tongue projecting from the intermediate portion of said spring, said finger having a reflex bend, there being corresponding apertures in the flanges of said bracket and in said spring-tongue and in said reflex bend, the apertures in said spring-tongue and in the reflex bend of said finger being elongated to permit rocking movement of said finger against the resistance of said spring, and a pivot-screw passing through all of said apertures to retain said parts.

6. In a typewriting machine having a revoluble platen and a carriage therefor, a paper-finger mounted on said carriage having means to contact with said platen, including a loop and means to deflect the leading edge of a work-sheet under said finger consisting of an arched member beneath said finger connected to said loop and terminating in a second loop secured to said finger between the extremities thereof.

7. In a typewriting machine having a revoluble platen and a carriage therefor, a folding paper-finger pivotally mounted at one extremity thereof on said carriage, including an integral strip of sheet-metal formed into a bracket at the mounted extremity, into a loop at the other extremity, and provided beneath with a concavely-arched member connected to said loop at one end thereof and bent at the other end to

meet an intermediate portion of said finger.

8. In a typewriting machine having a revoluble platen and a carriage therefor, a folding paper-finger pivotally mounted at one extremity thereof on said carriage, including an integral strip of sheet-metal formed into a bracket at the mounted extremity and into a loop to contact with said platen at the other extremity, a concavely-arched paper-guiding rib merging at one end in said loop and bent at the other end to join an intermediate portion of said finger, and a convexly-arched intermediate member upon said paper-finger to serve as a finger-piece.

9. In a typewriting machine having a shiftable platen and a carriage therefor, a folding paper-finger arranged to contact with the platen above the printing line, means upon said carriage for resiliently mounting said finger to permit the same to

swing about a vertical axis into folded position, and limit means combined with said first means to permit said finger to swing upwardly for platen-shifting and the insertion of work-sheets.

10. In a typewriting machine having a platen mounted on a carriage, a paper-finger resiliently mounted thereon, a loop on said finger normally bearing against said platen, and an arched paper-deflector integral with said loop and merging therewith, located beneath said finger.

11. In a typewriting machine having a revoluble platen and a carriage therefor, a paper-finger mounted on said carriage, having means to contact with said platen, and means to deflect a leading edge of a work-web towards said platen, including an arcuate paper-deflector supported at both extremities by said finger.

WILLIAM F. HELMOND.
